UNITED STATES PATENT OFFICE.

JOHN M. FEEDERS, OF BUFFALO, NEW YORK, ASSIGNOR TO FEEDERS MANUFACTURING COMPANY, INC., OF BUFFALO, NEW YORK, A CORPORATION OF NEW YORK.

RADIATOR.

1,296,785.

Specification of Letters Patent. Patented Mar. 11, 1919.

Application filed January 16, 1918. Serial No. 212,040.

To all whom it may concern:

Be it known that I, JOHN M. FEEDERS, a citizen of the United States, residing in Buffalo, in the county of Erie and State of New York, have invented new and useful Improvements in Radiators, of which the following is a specification.

This invention relates to a radiator for cooling the water of automobile gas engines and the like in which a plurality of tubes are arranged side by side so as to form water passages between adjacent tubes and air passages through the several tubes.

The object of this invention is to provide improved means for increasing the radiation of the heat of the water to the air as the same passes through these tubes, which improvements are intended to simplify the construction, reduce the cost of manufacture and also increase the radiating efficiency of the radiator as a whole.

In the accompanying drawings:

Figure 1 is a front elevation, partly in section, of a radiating core embodying my improvements. Fig. 2 is a longitudinal section taken in line 2-2, Fig. 1. Fig. 3 is a perspective view of one of the radiator sections forming part of the radiating means arranged in one of the air conduits. Fig. 4 is a similar view of one of the retaining members whereby a plurality of radiating sections are held in place within one of the air tubes.

Similar characters of reference refer to like parts throughout the several views.

The body of the radiator-core with which my improvements are associated comprises a plurality of tubes which are arranged side by side and each of which is provided with enlarged end portions 1, 1, and a contracted central part 2. These tubes are preferably constructed of sheet metal and of hexagonal form in cross section, although the same may be otherwise constructed, if desired. In assembling a plurality of such tubes, the facets of the large ends of each tube engage with corresponding facets of adjacent tubes so that the several enlargements of these tubes form heads on opposite sides of the radiator core while the spaces between the contracted central parts of adjacent tubes form water passages 3 through which the water of the engine to be cooled is circulated and the air which carries away the heat of this water to

the atmosphere passes through the air conduits 4 formed by the bores of the several tubes.

In order to increase the radiating capacity of these air tubes or conduits, radiating means are arranged in each of these tubes which radiating means are preferably constructed as follows:

Arranged in an annular row within each air tube is a plurality of radiating sections or members each of which is preferably constructed of sheet metal of substantially U-shaped form in cross section and has its web 5 arranged innermost while its longitudinal flanges 6, 6 project outwardly from opposite edges of the web, the arrangement of these flanges being substantially radial with reference to the axis of the air tube in which the same are arranged. At its outer longitudinal edge each of these flanges is provided at its ends with laterally-projecting salient edge portions 7, 7 which are adapted to engage with the bore of the enlargements at opposite ends of one of the air tubes and an intermediate receding edge portion 8 which engages with the bore of the contracted central part of the respective air tube. When a radiating section is thus engaged with one of the air tubes, the enlargements at opposite ends of the flanges of the radiating section interlock with the outwardly-facing shoulders formed in the bore of the respective air tube between its enlarged end parts and its contracted central part so that longitudinal displacement of this radiating section in the air tube is prevented.

In order to utilize the metal which is displaced from the central parts of the outer edges of the flanges of these radiating sections for producing a receding bearing surface on the respective parts, this metal is bent outwardly and inwardly on these flanges so as to form radiating lips or lugs 9 on these parts of these flanges, which lips are arranged at an angle relatively to these flanges on the outer sides thereof and preferably tangentially with reference to the axis of the respective air tube, so that the same do not contact with the bore of the latter.

Although the number of radiating sections within each air tube may be varied, it is preferable to employ three of them as shown in the drawings, inasmuch as by this means six radiating flanges 6 are provided

each of which engages an inner corner of the bore of one of the hexagonal air tubes and an equidistant arrangement of the flanges of the several radiating sections in each set 5 is by this means obtained.

After a group or set of radiating sections has been thus introduced into one of the air tubes, the same are held in place by a retaining member which engages with the inner 10 sides of the several radiating sections of each set. In its preferred form this retaining member is constructed of sheet metal in the form of a resilient tube 10 which is split lengthwise, as shown at 11. This retaining 15 tube is preferably hexagonal in cross section and engages each of its outer facets with the inner side of the web of one of the radiating sections. In assembling this radiating tube with a set of radiating sections, this retaining tube is first contracted so that the 20 same will slip easily lengthwise into the space between the several radiating sections which surround the retaining tube and after this retaining tube has been fully inserted, 25 the same is permitted to expand and engage its outer facets with the inner sides of the webs of the respective set of radiating sections, whereby the outward pressure of this retaining tube, due to its resilience, will 30 cause the several radiating sections of this set to be pressed firmly outward and hold the outer edges of the flanges of these radiating sections in reliable engagement with the bore of the respective air tube.

For the purpose of reducing the amount of metal in the radiating means within each air tube, certain parts of its members may be perforated and stock removed where the same performs no useful function. For this 40 purpose the web of each radiating section may be provided with openings 12 as shown in Fig. 3, and each of the retaining tubes may be provided with openings 13, as shown in Fig. 4.

After the radiating means have been thus inserted in the air tubes and a plurality of such tubes have been assembled to form the water passages between the same, these assembled members are dipped at their opposite ends into a bath of solder, so as to connect the several air tubes with each other at their opposite ends and also connect each tube with the radiating means therein, thereby completing the radiator core.

In the completed radiator, means are provided for introducing the water at one end of the water conduits between the air tubes and withdrawing the same from the opposite end, this being accomplished in any suitable 80 and well known manner.

These radiating means within the air tubes are simple in construction, they can be easily made and assembled by the use of inexperienced help so that the cost of manufacture 85 is reduced to a minimum. Furthermore, a

radiator thus constructed has an increased radiation effect, the same is materially strengthened and the same has an ornamental appearance when viewed from either side thereof.

70

I claim as my invention:

1. A radiator comprising a tube, and radiating means arranged within said tube and comprising a plurality of radiating sections arranged in an annular row and each being of U-shaped form in cross section and having its web innermost and its flanges projecting outwardly into engagement with the bore of said tube, and a retaining member engaging with the webs of said radiating sections.

75

2. A radiator comprising a tube, and radiating means arranged within said tube and comprising a plurality of radiating sections arranged in an annular row and each being of U-shaped form in cross section and having its web innermost and its flanges projecting outwardly into engagement with the bore of said tube, and a tubular retaining member engaging with the bores of the several radiating sections.

80

3. A radiator comprising a tube, and radiating means arranged in said tube and comprising a plurality of radiating sections arranged in an annular row within the tube, and a resilient tubular retaining member which is split lengthwise and engages yielding with the inner sides of said row of radiating members.

85

4. A radiator comprising a tube, and radiating means arranged within said tube and comprising a plurality of radiating sections arranged in an annular row and each being of U-shaped form in cross section and having its web innermost and its flanges projecting outwardly into engagement with the bore of said tube, and provided at the outer edge of each flange with an inwardly projecting lip, and a retaining member engaging with the webs of the several radiating members.

100

5. A radiating member comprising a tube having enlarged ends and a contracted central part, and radiating means arranged in said tube and comprising a plurality of radiating sections each of which is of U-shaped form in cross section and has its web arranged innermost while its flanges project outwardly and each flange has laterally projecting end portions engaging with the enlargements of said tube and a receding intermediate portion engaging with the contracted part of said tube, and a retaining member engaging with the webs of the several radiating sections.

115

6. A radiating member comprising a tube having enlarged ends and a contracted central part, and radiating means arranged in said tube and comprising a plurality of radiating sections each of which is of U-

120

130

shaped form in cross section and has its web arranged innermost while its flanges project outwardly and each flange has laterally projecting end portions engaging with the enlargements of said tube and a receding intermediate portion engaging with the contracted part of said tube and each flange be-

ing also provided on its intermediate receding edge portion with an inwardly projecting lip, and a retaining member engaging 10 with the webs of the several radiating sections.
